UNITED STATES PATENT OFFICE.

LOUIS N. BLUST, OF NEW ALBANY, INDIANA.

SPINAL-COLUMN MASSAGER.

Specification of Letters Patent.

Patented Apr. 18, 1916.

1,179,603.

Application filed October 14, 1915. Serial No. 55,894.

To all whom it may concern:

Be it known that I, LOUIS N. BLUST, a citizen of the United States, residing at New Albany, in the county of Floyd and State of Indiana, have invented certain new and useful Improvements in Spinal-Column Massagers; and I do declare the following to be a full, clear, and exact description of the invention, such as will enable others skilled in the art to which it appertains to make and use the same.

This invention relates to massaging machines and is of the type adapted for manipulating the back adjacent the spinal column in a manner similar to the osteopathic treatment of the spine.

One object of the invention is to provide a simply constructed machine which can be readily operated by any one.

20 A further object is to provide an adjustable support on which the legs of the user of the device are adapted to rest when the machine is in operation.

With the above general objects in view, 25 the invention consists in certain novel features of construction, combination and arrangement of parts which will hereinafter be more particularly described and claimed.

In the accompanying drawings; Figure 1 30 represents a side elevation of my improved machine; Fig. 2 is a top plan view thereof; Fig. 3 is a central vertical longitudinal section taken on the line 3—3 of Fig. 2; Fig. 4 is a transverse section taken on the line 35 4—4 of Fig. 3; Fig. 5 is a detail longitudinal section taken on the line 5—5 of Fig. 2; Fig. 6 is a detail perspective view of the slide.

In the preferred form of my invention I 40 provide a frame 1 which comprises a head end 2 and a foot end 3 connected by the longitudinal brace rods or hand rails 4. These rails 4 are preferably placed adjacent the outer ends of the members 2 and 3 while a 45 pair of spaced apart tracks 5 are secured to the ends 2 and 3 substantially in their center. These tracks 5 are adapted to support a slide 6 shown as formed of two parts 6' and 6'' which are connected by a tongue 7 adapted 50 to depend between the tracks 5 and to act as a guide for the slide when the same is reciprocated on said tracks. The frame 1 and the slide 6 are preferably constructed of wood, therefore the upper faces of the 55 tracks 5 are provided with metallic wear

plates 8, similar plates 9 being placed on the lower faces of the slide 6 which contact with the tracks 5. The members 6' and 6'' of the slide have their upper edges rounded as shown at 10 for a purpose to appear. 60 Operating handles 11 are formed on the opposite sides of the slide 6 for moving the same along the tracks.

The frame 1 is designed primarily to support a pair of flexible elements or strands 12 65 connected by their opposite ends to the end members 2 and 3 of the frame, and are adapted to support the weight of the person desiring to use this improved machine. These elements 12 rest one on each side of 70 the spinal column and extend substantially throughout the length of the user's back. It is obvious that because of their flexibility, they will conform to the curvature of the back of the person lying thereon and readily 75 give with any movement of the back. While these elements 12 may be constructed of any suitable flexible material, I preferably use a pair of tubes in each of which is placed a coil spring 13 whose opposite ends are provided with eyes 14 in which hooks 15 formed on plates 16 are placed. The plates 16 are secured by suitable attaching means to the members 2 and 3 of the frame as disclosed 80 in the various figures. This arrangement 85 allows the flexible elements to be readily removed from the frame for any purpose. Suitable guards 12' cover the opposite ends of the flexible tubes and the springs in order that the user of the device may not be injured by any sharp corners. These flexible tubes may be of any preferred construction but are here shown as formed of an endless spiral strip of metal 17 having an offset 90 portion 18 adapted to underlie the adjacent portion of the strip 17. This offset portion 18 is substantially an additional endless strip underlying the outside strip 17, the construction of the two being illustrated in 95 Fig. 5. Bands of rubber or other flexible material 17^a are placed between the outside strip 17 and the offset portion 18 in order 100 that the tube may be as elastic as possible.

As the flexible elements 12 extend only 105 the length of the person's back, I provide a head rest 19 hinged to the end 2 and adapted to fold against said end when the machine is not in operation, and to extend at right angles thereto when the device is in use, a suitable pivoted arm 20 having a notch in 110

its free end for engagement with a plate 21 being provided for holding the head rest in elevated position. This arm 21 is adapted to be inserted through the slot 22 in the end 2 5 when the head rest is folded.

The opposite end of the frame 1 is also provided with a slot 23 adapted to receive a shank 24 of a hinge member, the head 25 of which has pivoted thereto a leg support 26. 10 This leg support may be of any preferred construction but is here shown as formed of side members 27 which are tapered from their inner toward their outer ends and are covered on their upper edges by the cover 15 28 upon which the legs of the user are adapted to lie. The tongue 29 projects from the inner end of this support 26 and is pivoted to the aforementioned head 25 and carries a pivoted pawl for coaction with 20 ratchet teeth 30 formed on the edge of said head. From this description it will be seen that this leg support 26 may be readily elevated to any desired position and may be held in that position by the pawl and ratchet 25 connection just described.

To operate the massaging machine, the person desiring to take a treatment, lies on the flexible elements or tubes 12, said tubes bending downwardly and conforming to the 30 curvature of the back of the person. The slide 6 is then moved until it lies beneath the small or curved portion of the person's back. When the parts of the machine are in operative position, the person grasps the hand 35 rails 4 and moves himself backwardly and forwardly in a longitudinal direction on said elastic tubes. This operation causes the muscles of the back and the spinal column of the person taking the treatment to be 40 thoroughly manipulated and massaged.

The flexible tubes which support the person are designed to rest one on each side of the spinal column, as hereinbefore stated, and are held in this position by the grooves 45 32 formed in the curved faces 10 of the slides as best illustrated in Figs. 4 and 6.

From the foregoing description of the construction and operation of this improved massaging device, it is evident that I have 50 produced a machine which, while very simple in construction, may be very readily operated by even an unskilled practitioner and that it will be found to be extremely efficient.

55 I claim:

1. A device of the class described comprising a frame, a flexible element connected by its ends to said frame and adapted to support a person lying thereon, a slide movable beneath said element and adapted to underlie the curved portion of the person's back.

60 2. A device of the class described comprising a frame, an elastic element connected by its ends to said frame and adapted to

support a person lying thereon, a curved slide movable beneath said element and adapted to underlie the curved portion of the person's back.

3. A device of the class described comprising a frame, a pair of spaced apart flexible elements connected by their ends to the frame and adapted to rest one on each side of a person's spinal column and to support the weight of the person, a track carried by the frame beneath said elements, a slide movable to a plurality of positions thereon and adapted to underlie the curved portion of the person's back. 75

4. A device of the class described comprising a frame, a pair of spaced apart elastic elements adapted to rest one on each side of a person's spinal column and to support the weight of the person, a track carried by the frame beneath said elements, 80 a two-part slide movable to a plurality of positions thereon, each part being adapted to underlie one of the elastic elements beneath the curved portion of the person's back.

5. A device of the class described comprising a frame, a pair of spaced apart elastic elements adapted to rest one on each side of a person's spinal column and to support the weight of the person, a pair of 85 spaced apart track members carried by the frame beneath said elements, a two-part slide movable to a plurality of positions thereon and having a tongue depending between said track members, each part being 90 adapted to underlie one of the elements beneath the curved portion of the person's back.

6. A device of the class described comprising a frame, a pair of spaced apart 105 elastic tubes connected by their ends to the frame and adapted to rest one on each side of a person's spinal column and to support the weight of the person, a track carried by the frame beneath said tubes, a slide movable to a plurality of positions thereon, said slide being grooved on its upper edge to receive the tubes and adapted to underlie the 110 curved portion of the person's back.

7. A device of the class described comprising a frame, a pair of spaced apart elastic tubes, a coil spring in each of said tubes connected by their opposite ends to the frame, said tubes being adapted to rest one on each side of a person's spinal column and to support the weight of the person, a track carried by the frame beneath said tubes, a slide movable to a plurality of positions thereon and adapted to underlie the 115 curved portion of a person's back.

8. A device of the class described comprising a frame, a pair of spaced apart elastic tubes connected by their ends to the frame longitudinally thereof and adapted to rest one on each side of a person's spinal 120 125 130 column.

- column and to support the weight of the person, a track secured to the frame below said tubes, a slide movable to a plurality of positions thereon and adapted to underlie the curved portion of the person's back, and hand rails secured to said frame and extending parallel to said tubes, whereby the person lying on said tubes may move himself thereon.
9. A device of the class described comprising a frame, a pair of spaced apart elastic tubes connected by their ends to the frame longitudinally thereof and adapted to rest one on each side of a person's spinal column and to support the weight of the person, a track secured to the frame below said tubes, a slide movable to a plurality of positions thereon and adapted to underlie the curved portion of the person's back, hand rails secured to said frame and extending parallel to said tubes, whereby the person lying on said tubes may move himself thereon, a head rest secured to said frame adjacent one end of said tubes, and a vertically adjustable leg support at the opposite end of said frame.
10. A device of the class described comprising a frame, a pair of spaced apart elastic tubes connected by their ends to the frame longitudinally thereof and adapted to rest one on each side of a person's spinal column and to support the weight of the person, a track secured to the frame below said tubes, a slide movable to a plurality of positions thereon and adapted to underlie the curved portion of the person's back, hand rails secured to said frame and extending parallel to said tubes, whereby the person lying on said tubes may move himself thereon, and a head rest secured to said frame adjacent one end of said tubes.
11. A device of the class described comprising a frame, a pair of spaced apart elastic tubes connected by their ends to the frame longitudinally thereof and adapted to rest one on each side of a person's spinal column and to support the weight of the person, a track secured to the frame below said tubes, a slide movable to a plurality of positions thereon and adapted to underlie the curved portion of the person's back, hand rails secured to said frame and extending parallel to said tubes, whereby the person lying on said tubes may move himself thereon, and a foldable head rest secured to said frame adjacent one end of said tubes.
12. A device of the class described comprising a frame, a pair of spaced apart elastic tubes connected by their ends to the frame longitudinally thereof and adapted to rest one on each side of a person's spinal column and to support the weight of the person, a track secured to the frame below said tubes, a slide movable to a plurality of positions thereon and adapted to underlie the curved portion of the person's back, hand rails secured to said frame and extending parallel to said tubes, whereby the person lying on said tubes may move himself thereon, a head rest secured to said frame adjacent one end of said tubes, and a vertically adjustable leg support at the opposite end of said frame.
13. A device of the class described comprising a frame, a pair of elastic elements secured by their opposite ends to the opposite ends of the frame, said elements being adapted to rest one on each side of a person's spinal column and to support the weight of the person, a pair of spaced apart track members secured to the frame below said elements, one end of said frame being slotted, a slide movable to a plurality of positions on said track members and adapted to underlie the curved portion of the person's back, an adjustable leg support adjacent one end of the elements, a hinged member having a shank adapted to be inserted in said slot, the head of said leg support being pivoted to said member, and a pawl and ratchet connection between said member and the support for adjusting the same.
14. A device of the class described comprising a pair of flexible strands adapted to rest one on each side of the person's spinal column, a frame upon which said strands are mounted, and a support beneath said strands adapted to underlie the curved portion of the person's back, said support and frame being movable relative to each other.
- In testimony whereof I have hereunto set my hand in presence of two subscribing witnesses.
